KURT BAUCH AND PAUL HELMA, OF AKRON, OHIO, ASSIGNORS TO GOODYEAR-ZEP-
PELIN CORPORATION, OF AKRON, OHIO, A CORPORATION OF DELAWARE

NONRIGID AIRSHIP

Application filed September 26, 1929. Serial No. 395,371.

This invention relates to non-rigid airships, and it has particular relation to the suspension of pilot cars or gondolas from the envelopes of non-rigid airships.

The principal object of the invention is to provide a non-rigid airship in which the envelope and the pilot car or engine car are so constructed as to offer the minimum air resistance.

Another object of the invention is to provide connections between the envelope and pilot car that are not exposed to the air-stream for sustaining the weight of the pilot car, as well as stabilizing it against lateral or longitudinal movement.

In non-rigid airships of the type previously constructed, pilot cars for carrying passengers and engines were suspended at considerable distance from the airship envelope by means of relatively long and numerous cables which were connected to patches at various locations along the outer surface of the envelope. Suspension cables of such length and number offered excessive air resistance, and the car and envelope were capable of excessive relative movement. Moreover, handling of the airship at the ground involved considerable difficulty and inconvenience.

According to this invention the car is secured directly to the lower portion of the envelope of a non-rigid airship in an opening therein and is provided with connections directly to the edges defining the opening to prevent relative movement between the envelope and the car. Also, suspension cables for sustaining the weight of the car are connected directly to the upper inner portion of the envelope by means of one or more catenary curtains. Thus the airship is a compact unit having no space between the envelope and the car and no suspension cables extending into the air-stream.

For a better understanding of the invention, reference may now be had to the accompanying drawings, forming a part of the specification, of which:

Figure 1 is a side-elevational view of a non-rigid airship embodying the invention;

Figure 2 is a plan view of the bottom of a car connected to the airship envelope; and

Figure 3 is an end elevational view of the construction shown by Figure 2.

In practicing the invention, a non-rigid airship envelope 10 is provided with a car 11 and a conventional type of air balloon 12 for compensating for contraction and expansion of the gas in the envelope. At the lower portion of the envelope an opening 15 is cut in the form of catenaries having inwardly projecting angular portions 16 to which a plurality of laterally inwardly extending connecting elements 17, such as short cables or straps, are secured. A framework 18 of the pilot car is also connected to the elements 17, as indicated at 19. It will be observed that a plurality of the elements 17 extend from each connecting point 19 and are distributed among a plurality of the angular connecting portions 16. The edge portions of the envelope defining the opening 15 are preferably reinforced by elements 20, such as fabric or cables.

One or more rows of catenaries 22 secured longitudinally of the upper inner portion of the envelope are provided with a plurality of cables 23 and 24 which radiate from the ends 25 and 26, respectively, of a plurality of cables 27, that in turn extend through the balloon 12 and are connected to the pilot car.

From the foregoing description it will be apparent that by employing connecting elements, such as those described, the upper framework of the pilot car is securely mounted against the lower side of the envelope and is prevented from shifting with respect thereto while the load or weight is suspended from the upper portion of the envelope. The width of the car is such that it will be prevented from tilting with reference to the lower portion of the envelope. Longitudinal or transversely directed forces to which the pilot car may be subjected are transmitted directly into the envelope without the aid of exterior suspension cables. This arrangement greatly simplifies the construction of non-rigid airships and facilitates the navigation thereof.

Although we have illustrated only one form which the invention may assume and have described that form in detail, it will be apparent to those skilled in the art, that the invention is not so limited, but that various modifications may be made therein without departing from the spirit of the invention or from the scope of the appended claims.

What we claim is:—

- 10 1. A non-rigid airship comprising an envelope, catenaries disposed about the lower portion of the envelope, a car connected along the catenaries directly against the lower portion of the envelope, suspension elements extending upwardly from the car, and means for connecting the upper portion of the suspension elements inside the envelope.
- 15 2. A non-rigid airship comprising an envelope provided with an opening defining catenaries, a car covering the opening, means for connecting the car to the catenaries, and means for connecting the car to the upper inner portion of the envelope.
- 20 3. A non-rigid airship comprising an envelope provided with an opening in the lower portion thereof, the edges of the envelope defining the opening being in the form of catenaries, a car, connecting means disposed laterally about the car and secured along the edges of the portion of the envelope forming the catenaries, and suspension means connected to the upper inner portion of the envelope and to the upper portion of the car for suspending the latter.
- 25 33 In witness whereof, we have hereunto signed our names.

KURT BAUCH.
PAUL HELMA.
